UNITED STATES PATENT OFFICE.

THOMAS W. BRYANT, OF ANSONIA, CONNECTICUT.

HOLDER FOR INCANDESCENT LAMPS.

SPECIFICATION forming part of Letters Patent No. 310,373, dated January 6, 1885.

Application filed May 2, 1884. (No model.)

To all whom it may concern:

Be it known that I, THOMAS W. BRYANT, of Ansonia, in the county of New Haven and State of Connecticut, have invented a new Improvement in Holders for Incandescent Lamps; and I do hereby declare the following, when taken in connection with accompanying drawings and the letters of reference marked thereon, to be a full, clear, and exact description 5 of the same, and which said drawings constitute part of this specification, and represent, in—

Figure 1, a side view of the holder and lamp attached; Fig. 2, a vertical central section; Fig. 15 3, an under side view of the head, showing the connection between the wire from the upper end of the springs and the line-wires, all the figures enlarged.

This invention relates to an improvement in 20 the construction of holders for incandescent lamps, the object being to make the lamp readily detachable, yet insure perfect contact when in place; and the invention consists in the construction of the holder, as hereinafter 25 fully described, and more particularly recited in the claims.

A is the metal socket by which the holder is secured; B, the body of the holder, made of wood or other suitable material, and into 30 which the tip of the socket is screwed or otherwise applied. The upper end of the body is inclosed by a metal cap, C.

In the lower end of the body are two vertical recesses, a b. Into each of these recesses 35 a helical spring, respectively, d e, is introduced, the diameter of the spring being somewhat less than the recess, so as to leave perfect freedom of the spring. The wire from the upper end of each spring is continued upward through a 40 hole leading from the respective recesses, thence returned through another hole to the bottom of the body, where the ends are secured, respectively, by screws f g.

Centrally through the body is an opening, 45 through which the two line-wires h i extend. These run downward to the lower end of the body, and are turned and secured by the same screws, f g, which secure the wires of the 50 respective springs, and thereby make contact between the line-wires and the springs. The

lower ends of the springs d e are bent to form hooks, respectively, l m.

Upon the outside the body is reduced to form an annular shoulder, n. Around the body and against this shoulder a helical spring, o, 55 is arranged, free for vertical extension or contraction. Surrounding this spring is a metallic shell, p. This shell extends up onto the outer surface of the cap C, as shown, and below the spring is contracted to form an internal shoulder, r, against which the lower end of the spring o bears, and so that the tendency of the spring—the upper end bearing against the shoulder n, and its lower end against the shoulder r—is to force the shell p downward. 60 The lower end of this shell is open and constructed with downwardly-projecting and outwardly-curved fingers s, to embrace the neck of the lamp D. The lamp is constructed in the usual manner, and consists of a small glass 70 globe terminating in a neck at its upper end, and through which the two wires t u pass, and within the globe support the carbon. The lamp itself, constituting no part of my invention, therefore, does not require to be particularly 75 described. The two wires t u terminate, respectively, in hooks v w, and so as to engage, respectively, the hooks l m at the lower end of the springs d e, as shown, and when engaged, as seen in Fig. 2, the shell p is forced 80 down by the action of the spring o tending to force the lamp downward, at the same time the springs d e are tending to draw it upward, whereby a firm metallic contact is made between the two wires at the respective hooks, 85 l v and m w, and such a contact as cannot be accidentally broken. The shell p is free to slide up and down upon the cap C.

Through the shell p are one or more vertical slots, E, and through these slots a pin, F, 90 is introduced into the body B, but so as to permit the up and down movement of the shell p. The lower end of these slots is turned at right angles, as at G. Now, if the shell be moved upward so far as to bring the right-angular portion of the slot G into line with the pin F, and the shell be turned to take the horizontal portion G of the slot onto the pin, the shell will be held in that elevated position, as seen in broken lines, Fig. 2, and in thus rais- 95 100

ing the shell the spring *o* is compressed. At the same time the lamp itself is relieved from the downward pressure or force of that spring, permitting it to be raised, and so that the hooks *l v* and *m w* may be readily disengaged.

The fingers *s* embrace the neck of the lamp with sufficient frictional force to hold the lamp. Therefore when the shell *p* is raised it carries the lamp with it, and to such an extent 10 that the hooks *v w* are raised from substantial contact with the hooks *l m*, and in which condition the circuit is broken, and will so remain broken until the shell *p* be turned to bring the vertical portion *E* of the slot into line with 15 the pin *F*. Then the spring *o* will react, force the shell *p* downward, and with it the lamp, to again make contact between the hooks *l v* and *m w*.

By this construction not only is positive contact assured when required, but that contact is easily broken by simply raising the shell *p* 20 and locking it in its raised position. When the shell is so raised the lamp may be easily removed by simply drawing it from the grasp 25 of the fingers *s s* and disengaging the hooks, or replaced by reversing the operation.

It will be understood that the wires *h i* are insulated, and that the upward extension from the springs as it passes over the top of the 30 body is insulated from the cap, either by material introduced between the cap and the head over the bend in the wires, as shown, or otherwise.

While I prefer to employ the spring *o* it 35 may be omitted, the sleeve being constructed to slide upon the body with sufficient friction to hold it in either position, up or down; or the slot *E* may be constructed with a right-angular projection therefrom at its upper end, 40 so that the sleeve may be turned to lock it either in its up or down position. In the omission of the spring *o*, the forcible contact will be made by the springs *d e* only. The spring *o* serves to make this contact more firm.

45 I am aware that springs have been arranged in incandescent lamps, one end of each spring in connection with the respective wires of the

circuit, the other ends of said springs in connection with the carbons, and with a sleeve arranged to move to and from and so as to 50 embrace the neck of the globe, and therefore make no claim to such construction.

I claim—

1. The herein-described holder for incandescent lamps, consisting of the body *B*, constructed with vertical recesses *a b*, a helical spring in each of said recesses, said springs at their lower end terminating in hook shape, the other end of the springs in connection with the respective line-wires, a surrounding 60 shell, *p*, helical spring *o*, the said shell constructed at its lower end to embrace the neck of the globe, the lamp provided with the two hooks *v w*, in connection with the carbon in the lamp, and so as to engage the respective 65 hooks *l m* of the holder, substantially as described.

2. The combination of the body *B*, line-wires extending downward through the body, the body constructed with recesses *a b*, helical 70 springs arranged in said recesses, their upper end continued through the body and returned to the lower end and there connected with the line-wires, the lower end of the springs constructed to form hooks *l m*, the vertically- 75 movable shell *p*, constructed at its lower end to embrace the neck of the lamp, and the wires from the carbon in the lamp constructed to engage the said hooks *l m*, substantially as described.

3. The combination of the head *B*, helical springs *d e*, one end of each in connection with the respective line-wires, the other end constructed to engage the respective wires from the lamp, the vertically-movable shell *p*, 85 constructed at its lower end to embrace the neck of the lamp, and also constructed with the L-shaped slot *E G*, and the spring *o*, all substantially as and for the purpose described.

THOS. W. BRYANT.
